AUTOMATIC SPRINKLER SYSTEM

William B. Griffith, Audubon, N. J.

Application May 24, 1939, Serial No. 275,419

6 Claims. (Cl. 169—17)

My invention relates to automatic sprinkler systems for fire protection, employing a tank for supplying liquid to a distributing pipe, having sprinkler heads. Air under pressure in the tank is balanced by like pressure in said pipe above the level of the liquid. When a sprinkler head opens, the pressure in the tank forces the liquid through the pipe and the open heads.

Heretofore a restricted air passage between the tank and the pipe has been employed for allowing the pressure to equalize and maintain the liquid in the pipe at the same level as in the tank when leakage occurs in the system above the liquid in the pipe. When a sprinkler head would open the air under pressure from the tank would continue to flow through said air passage and retard the initial rise of liquid in the pipe. Means have also been employed for closing said air passage, which means were actuated by the rise of liquid by the opening of a sprinkler head, and the flow of liquid was retarded by the air under pressure being admitted to the distributing pipe during the time required for the liquid to rise to the required level for closing said air passage.

The object of my invention is to increase the speed of operation of the discharge of liquid from the tank through the distributing pipe when a sprinkler head opens.

A further object is to provide a system in which all the air under pressure is confined within the tank for imparting a rapid initial movement of the liquid from the tank to the distributing pipe, and the admission of air to said pipe from the tank above the liquid level is entirely cut off, so that the flow in said pipe will not be retarded when a sprinkler head opens, and all the air in the tank is utilized for forcing the liquid from the tank to the sprinkler heads.

A further object is to provide a normally closed valve in an air passage between the tank and the distributing pipe for sealing the air in the tank so that a gradual change in the liquid level in the pipe will occur in the event of leakage of air from the system above the liquid in the pipe.

A further object is to provide valve opening means actuated by a gradual rise of liquid in the pipe for equalizing the pressure in the tank and the pipe and thereby restoring the liquid level in the pipe to the liquid level in the tank.

A further object is to construct said valve opening means in the form of a float arranged within a chamber located above the normal liquid level in the pipe, so that the weight of the valve and the float will close said valve when the pres-

sure is equalized and the liquid level is below the float.

A further object is to arrange the float so that it will lose its buoyancy, and will not tend to open the valve, when the float chamber is filled with liquid.

A further object is to provide alarm actuating means which is operated independently of the valve operating means.

These together with various other novel features of construction and arrangement of the parts which will be more fully hereinafter described and claimed constitute my invention.

Referring to the accompanying drawing:

Fig. 1 is a vertical sectional view showing a sprinkler system embodying my invention.

Fig. 2 is a horizontal section on line 2—2 Fig. 1.

In the drawing in which like reference characters refer to like parts, 3 represents a closed tank which is partly filled with liquid through a pipe 4, and adapted to contain air under pressure above the liquid.

A distributing pipe, or riser, 6 is connected at its lower end with the tank 3 and is in communication with the lower portion of the latter. Said pipe 6 forms part of a closed sprinkler system including branch pipes 7 and automatic sprinkler heads 8. A valve casing 10 is coupled between sections of the distributing pipe. Said casing has an axial tubular core 12 forming a passageway in alignment with the sections of the pipe 6.

The system is charged with air under pressure from a supply pipe 14, having a check valve 15, through which the air is supplied to the pipe 6 through a pipe 16, and supplied to the tank 3 through pipes 17 and 18. The pipe 17 is provided with a check valve 19. Said check valves 15 and 19 prevent the flow of air toward the supply pipe 14. After the system has been charged with air, the air supply through the pipe 14 is shut off by means of a suitable valve, not shown in the drawing.

The casing 10 is provided with a sealed valve chamber 20, which is connected with the pipe 18, leading to the tank, by a pipe 21, through which pipes the pressure is admitted to the valve chamber 20.

A normally closed air valve 25 is located in said chamber 20 and is adapted to close upon a seat 26 surrounding a port 27, formed through a wall of the casing 10 and separating the valve chamber 20 from a float chamber 39, which latter is in communication with the distributing pipe 6.

through apertures 31 and 32 formed in the core 12 of the casing. The valve 25 is arranged so as to be held closed upon its seat by a preponderance of pressure confined in the tank and in the 5 chamber 20, in the event of a sudden reduction of the pressure in the pipe 6, caused by the opening of a head 8. Said valve 25 is automatically closed by gravity when the air pressure in the tank is equalized with the pressure in the pipe 6.

10 The valve 25 is secured upon a stem 33 which extends through the port 27 and into the float chamber 30. A float 35 is secured to the lower end of the stem 33 and is adapted for lifting the valve 25 from its seat when the liquid rises in the pipe 6 and enters the float chamber 30. When there is a slight reduction in the pressure in the pipe 6, due to leakage of air from the latter, the liquid level in the pipe 6 will rise gradually by the action of the relatively higher pressure confined in the tank. When the liquid enters the chamber 30 it will lift the float 35 and open the valve 25 against a slightly higher pressure in the tank relatively to that in the pipe 6. 15 When there is a great difference between the pressure in the tank relatively to that in the pipe 6, due to the opening of a sprinkler head, the differential pressure acting upon the upper side of the valve 25 will be so great that the float 20 will not open said valve, thus confining all the air under pressure within the tank for forcing the liquid from the tank through the pipe 6 to the open sprinkler head.

25 The float, or container 35, is cup-shaped so that it will be filled with liquid when the latter continues to rise in the pipe 6, thus negativing the buoyancy of the container. The filling of the container with liquid will prevent the container acting as a float and opening the valve 25, when 30 the air pressure in the tank is nearly exhausted by the forcing of the liquid through the pipe 6 to the open sprinkler heads.

35 The casing 10 is provided with alarm apparatus 38, comprising a lever 39 pivoted in a flexible bearing 40 mounted upon the casing above the level of the float 35. Said lever has an arm 41 extending into a second float chamber 42, and an arm 43 extending through the wall of the casing and arranged for tilting a mercury switch 45, 40 for controlling an electric circuit including an alarm device 46.

45 A ball float 47 is located in the chamber 42 formed within the casing 10 and communicating with the pipe 6 through apertures 48 and 49 formed through the core 12. Said float 47 is adapted to engage the arm 41 of the lever and actuate the alarm when the liquid continues to rise in the pipe 6 due to the opening of a sprinkler head, or due to the failure of the valve 25 50 to open and the liquid continues to rise due to a slow leak in the pipe 6.

55 The operation of my invention is as follows: The tank 3 and the pipe 6 are partly filled with liquid. Air under pressure is forced into the tank and the pipe above the liquid for filling the system, which is closed by a sprinkler head, for maintaining the liquid in the pipe at the same level as that in the tank.

60 The air under pressure is confined within the tank by the normally closed air valve 25, and the check valve 19. Any reduction in the pressure in the pipe 6, due to leakage of air from the system, will cause the pressure in the tank to force the liquid in the pipe 6 to a higher level than 65 that in the tank.

When the liquid rises in the pipe 6 it will enter the chamber 30 and lift the float 35 which will open the valve 25, so that the pressure in the pipe 6 will equalize with the pressure in the tank and thus restore the liquid level in the pipe to 5 the liquid level in the tank, and the valve 25 will close by its own weight when the pressure is equal on opposite sides of the valve.

Should the valve 25 fail to open, the liquid will continue to rise and overflow the container 35, 10 so that the latter will not act as a float, and the valve 25 will remain closed in the event of a sprinkler head opening.

When the liquid rises above the top of the container 35 and fills the chamber 42, the ball 15 float 47 will lift the arm 41 and tilt the switch 45, thereby closing the circuit and actuating the alarm for indicating a rise of liquid in the pipe 6, caused by the opening of a head 8, or for indicating the failure of the valve 25 to open in the 20 event of a slow reduction of pressure in the pipe 6 due to leakage.

Upon the opening of a sprinkler head the air under pressure will be reduced in the pipe 6 so that the valve 25 will be held closed upon its 25 seat by the relatively higher pressure in the tank, and all the air under pressure in the tank will be conserved for forcing the liquid from the tank through the pipe 6 to the sprinkler heads.

I claim:

1. A sprinkler system comprising a tank partly filled with liquid, a distributing pipe in communication with the lower portion of the tank and extending above the latter, said tank and pipe containing air under pressure above the liquid 35 level, a connection forming an air passage between the tank and pipe above the liquid level, means arranged for normally closing said passage when the pressure in the pipe and tank are equal and for sealing said passage by the action of a 40 relatively higher pressure in the tank in the event of a sudden reduction in the pressure in the pipe, and means actuated by a gradual rise in the level of the liquid in said pipe for actuating said first 45 named means for admitting the pressure from the tank to said pipe and restoring the liquid level in the pipe to that in the tank.

2. A sprinkler system comprising a tank partly filled with liquid, a distributing pipe in communication with the lower portion of the tank and 50 extending above the latter, said tank and pipe containing air under pressure above the liquid level, a connection forming an air passage between the tank and said pipe, a normally closed valve controlling said passage for confining said 55 pressure within the tank, and means actuated by a gradual rise of the liquid level in said pipe, due to leakage of air from the latter, arranged for opening the valve for equalizing the pressure in the pipe and tank.

3. A sprinkler system comprising a tank partly filled with liquid, a distributing pipe in communication with the lower portion of the tank and extending above the latter, said pipe and tank containing air under pressure above the liquid 65 level, a connection forming an air passage between the tank and said pipe, a weighted valve normally closing said passage when the pressure in said pipe is equal to the pressure in the tank, said valve arranged to be maintained closed by 70 a preponderance of pressure in the tank for sealing the latter upon the sudden reduction of air under pressure from said pipe, and means for opening said valve actuated by a gradual rise of the liquid level in said pipe, due to leakage of air 75

from the latter, for equalizing the pressure in the pipe and tank and restoring the liquid level in the pipe to that in the tank.

4. A sprinkler system comprising a tank partly filled with liquid, a distributing pipe in communication with the lower portion of the tank and extending above the latter, said tank and pipe containing air under pressure, a connection forming an air passage between the tank and said pipe above the level of the liquid, a normally closed valve controlling said passage for confining said pressure within the tank and causing a rise of the liquid level in said pipe in the event of leakage of air from the latter, and a float actuated by the rise of the liquid level in said pipe and arranged for opening said valve for equalizing the pressure in said pipe and tank and restoring the liquid level in said pipe to that in the tank.
5. A sprinkler system comprising a tank partly filled with liquid, a distributing pipe in communication with the lower portion of the tank and extending above the latter, said tank and pipe containing air under pressure, a connection forming an air passage between the tank and

said pipe above the liquid level, a normally closed valve controlling said passage for confining said pressure within the tank and causing a rise of the liquid level in said pipe in the event of leakage of air from the latter, a float chamber in communication with said pipe, a cup shaped float located in said chamber above the normal liquid level, said float adapted for opening said valve upon a gradual rise of the liquid level in said pipe relatively to that in the tank, and said float arranged to close said valve when the liquid continues to rise and fills said cup shaped float.

6. A casing having inlet and outlet pipe connections, said casing having a passageway formed through the same for the flow of liquid through said connections, said casing having a sealed air chamber formed therein, a pipe connection through which air under pressure is supplied to said chamber, said casing having a port forming a communication between said chamber and said passageway, a valve within said chamber normally closing said port, a float located within the casing, and a rod connecting said valve and the float adapted for opening the valve.
